CIRCULAR, INDEPENDENT NEEDLE,
KNITTING MACHINEBrooks Stevens, Jr., Concord, Mass., assignor to
Lawrence Manufacturing Company, Lowell,
Mass., a corporation of Massachusetts

Application September 23, 1948, Serial No. 50,826

13 Claims. (Cl. 66—19)

1

This invention relates to circular, independent-needle knitting machines for knitting unitary, tubular, plain-knit fabric having at least one relatively narrow, walewise extending area of rib knitting to serve as curl-preventing edges when the fabric has been cut lengthwise along a median line of such rib-knit area or areas, as disclosed in my Patent No. 2,414,424, January 14, 1947.

In order that the principle of the invention may be readily understood I have disclosed a single embodiment thereof in the accompanying drawings, wherein—

Fig. 1 is a front elevation of a circular knitting machine embodying my invention;

Fig. 2 is a plan view thereof; and

Fig. 3 is a detail in vertical section showing cylinder and dial needles.

In my said Patent No. 2,414,424 I have disclosed and have therein claimed an integral plain-knit fabric of indefinite length and the method of making the same, which fabric, excepting only for its walewise extending, relatively narrow, opposite, free edge portions, is plain knit, the said relatively narrow, opposite side portions being each of substantial width in a course-wise direction, but relatively narrow in comparison with the total width of the fabric when cut along a median line thereof to provide said free edge portions, and being rib-knit, and thereby rendered non-curling by reason of the drawing of the yarns of the fabric to the opposite faces of the fabric by the knitting of such rib-knit, ultimate edge portions, the character or structure of the fabric being that of a plain-knit fabric with rib-knit, ultimate lateral edges for the purpose stated.

My said patent describes the knitting of such fabric either as a tubular fabric having one or more such relatively narrow, longitudinally extending, rib-knit areas, which fabric, after it has been removed from the knitting machine, is cut along substantially a median line of such longitudinally extending, rib-knit area or areas, and also describes the knitting of such fabric as a flat, plain-knit fabric having the described narrow, rib-knit, longitudinally extending, lateral edges.

This application is directed to a circular knitting machine for knitting the described circular-knit fabric such as shown in Figs. 1 and 2 of my said patent. While my invention is not, of course, limited thereto, I have herein disclosed means for knitting such fabric with a single longitudinally-extending area of rib knitting. Means basically similar to that herein shown may be provided for knitting two or more such longitudinally extend-

2

ing, rib-knit areas. After the fabric has been knitted, it is removed from the machine and is cut lengthwise along the median line of said relatively narrow, rib-knit area, or if the fabric is knitted with two or more such areas, it is similarly cut along each of them.

My invention is not limited to any particular type of circular, independent needle knitting machine, nor to any particular diameter thereof.

10 Neither is it limited to a rotary needle cylinder, or to a rotary cam ring, and either latch needles or spring-beard needles may be employed. The disclosed embodiment of my invention, however, is of a circular knitting machine having a rotary needle cylinder and a surrounding stationary cam ring, independent latch needles being provided, and preferably a sinker ring is provided surrounding the needle cylinder. The sinker ring may be omitted and the yarns may be drawn by 15 the cylinder needles in descending over the tips of the tricks forming the walls of the needle grooves, as is well known. I also desirably provide a large number of stationary feeds for the yarns, so that in one revolution of the needle cylinder a preferably large number of courses are knitted equaling the number of stationary yarn feeds. The 20 yarn feeds will, however, rotate if the needle cylinder is stationary. In other words, the cam ring is provided with knitting cams at each feed, and 25 all the needles, including the narrow segment of dial needles, take yarn at all the feeds in each revolution of the needle cylinder.

I may and desirably do provide a needle cylinder having a diameter of, it may be, fourteen

35 inches, and I may and desirably do provide thirty-two stationary yarn feeds. These figures are given merely as an example, and impose no limitation upon the invention. I provide a dial which rotates with the needle cylinder (if the

40 needle cylinder rotates) and which may be a complete circle, or only a segment of sufficient width or extent to receive the desired number of dial needles. I therefore use the term "dial" to mean either a complete circular disk or a segment of a circular disk. I provide only sufficient dial needles in such a dial as to constitute a narrow segment of needles, thereby to knit one longitudinally extending stripe of rib knitting of the desired width. Such stripe may be and desirably is about two inches in width so that when the

50 fabric is cut along the median line of such stripe, there results a very wide plain-knit fabric having at each lateral, free edge a stripe of rib knitting about one inch in width, more or less. In order to cause the said narrow segment of

dial needles to knit a stripe of, say, two inches in width. I mount upon the top of the dial (which, if a complete circle, may otherwise be of the usual character, or, as stated, may be merely a segment thereof) a cam desirably in the form of a rotary disk having a plurality of cam lobes constituting a continuous cam track, so that in the rotation of the said cam disk with the needle dial, the dial needles, as they rotate with the cylinder needles, are projected so as to take a yarn at each feed, as do the cylinder needles. If there are as many as thirty-two stationary yarn feeds, and consequently thirty-two sets of knitting cams in the cam ring or cam cylinder, I provide the said cam disk, which is pivotally mounted upon the dial, with a number of cam lobes which may if desired be equally divisible into the number of yarn feeds. The number of cam lobes is, however, not essential, the only requisite being that in the operation of the parts, there be a cam lobe presented to the dial needles, whenever such dial needles are to be presented to one of the yarn guides to take yarn therefrom. Thus, for example, four cam lobes may be provided on said cam disk, and consequently the said cam disk will be rotated eight times upon its own axis during a single revolution of the said cam disk about the stationary cam ring of the knitting machine.

Thus the rotative and evolvable movement of the cam disk to present the dial needles is synchronized with the cylinder needle presenting action of the surrounding stationary cam ring, and particularly with the time of arrival of the dial needles at each yarn feed, so that the few dial needles co-act with the proper cylinder needles and the stationary yarn feeds.

Referring more particularly to the drawings, and therefore to that embodiment of my invention in which the needle cylinder rotates, the needle cylinder is represented at 1 in Fig. 3, and it may have any suitable diameter as, for example, fourteen inches or twenty-six inches. It is provided throughout with independent latch needles 2 provided with suitable butts for engagement with the cams of the surrounding stationary cam ring 3, shown in Fig. 1. Surrounding the upper edge of the needle cylinder is provided a suitable sinker ring 4. Suitably supported with relation to the needle cylinder 1 and the stationary cam ring 3 are a large number of herein, stationary yarn feeds which, if the needle cylinder has a diameter of fourteen inches, may be as many as thirty-two arranged in a circle about the top of the needle cylinder 1, and in suitable relation to the stationary set of knitting cams upon the cam ring 3, which would be thirty-two in number, if thirty-two yarn feeds are provided. In any case the number of yarn feeds equals the number of sets of knitting cams of the cam ring or cylinder at each of which sets the cylinder needles are elevated to take yarn and are depressed to cast off loops, the cylinder needles 2 cooperating with the sinkers of the sinker ring 4, if the latter be employed. The yarn ends are indicated at 6, and they are drawn down through suitable guides 7 from the yarn supply, consisting in this instance of thirty-two yarn packages stationarily supported above the needle cylinder and cam cylinder or ring.

The framing of the machine is indicated at 8. It is unnecessary to describe the structure of the knitting machine in detail which may be, as to its basic features, constructed in accordance with the Brinton Plain Jersey machine, style RMP, for the making of plain flat fabric, the machine

being a multiple feed machine of the revolving or rotary cylinder type, the yarns remaining stationary upon a suitable fixed support extending upward from the framing of the machine in a manner that need not be more particularly described. My invention is not limited to any particular type of circular, independent needle, knitting machine.

The needle dial is indicated at 9. It is here shown as a complete circle, but, as stated, it may be merely a segment thereof. It is or may be provided with dial needle grooves extending about the entire upper surface thereof, if a complete circular dial be provided, but I provide, as diagrammatically indicated at 10, a merely relatively narrow segment of dial needles which are only enough in number (not herein shown in their true number) to cooperate in knitting the single rib-knit stripe, referred to in the disclosed embodiment of my invention wherein provision is made for knitting only one longitudinally extending, rib-knit stripe. In order to provide means for causing the said segment 10 of dial needles to be projected and retracted at each yarn feed, so as to knit thereat, I herein provide the following construction, to which, however, my invention is not limited.

Two radially extending supports 11, 12 are provided which extend to the axial center of the needle cylinder and dial, as indicated in Fig. 2, and, as there shown, the said two radial supports 11, 12 are mounted upon or carried at their outer ends by two upright posts 13, 14, rising from the framing 8 of the machine. Any other suitable number of such radial supports may be provided, as, for example, three. At the axial center of the dial and needle cylinder, there is positioned an axial vertical shaft 15 which may be driven in any suitable way and at any suitable speed from the main drive shaft of the machine. Secured to the upper face of the dial 9 is a member 15' in the general form of a bar or segment which at its outer end may be of about the width of the entire segment of dial needles, and which at its inner end may terminate wherever desired. It may in fact be entirely omitted, and the gears next to be described (except the inner one) may be mounted directly upon the dial, whether that be of circular or segmental form. Fast, if desired, upon the axial shaft 15 is a central gear or pinion 17 so as to be driven by said shaft 15, in either direction but at a speed other than that at which the dial is driven, or the gear or pinion 17 may be held stationary and the dial may rotate about it.

Meshing with the said gear or pinion 17 is a pinion 18 and radially outside of the pinion 18 and meshing therewith is a toothed disk 19 having, in the disclosed embodiment of the invention, four cam lobes 20, 21, 22, 23, so as to provide the four portions 20', 21', 22' and 23' of the continuous cam groove which is upon the under face of the said disk 19, so as to engage with the butts of the dial needles, thereby projecting them to take yarn at each feed, and then retracting them. The disk 19 is herein referred to as a cam disk. The pinion 18 and the disk 19 are pivotally mounted on the under side of said bar or segment indicated at 15'. As stated the number of cam lobes may be greatly varied.

The needle cylinder 1 may be presumed to rotate contraclockwise, viewing Fig. 2, in which case the cam disk 19 rotates clockwise, the intermediate pinion 18 rotates contraclockwise and the gear pinion 17 rotates clockwise, or, as stated,

it may be held stationary. Any other suitable gearing may be provided, and the gearing is so designed and proportioned as, in the illustrated embodiment of the invention, to rotate the cam disk 19 upon its own axis eight times in one complete revolution of the needle cylinder 1 and the dial 9, assuming that there are thirty-two stationary yarn feeds. Any other suitable number of rotations of the cam disk 19 upon its own axis may be provided to synchronize with the yarn feeds in the manner stated.

It will be understood that each lobe of the cam disk 19 is so shaped that at each feed, all the dial needles of the segment 10 are projected to take yarn with the cylinder needles and then are retracted so as to knit a relatively narrow stripe of rib fabric. Thus the said synchronizing action is effected. At each feed the said segment 10 of dial needles takes the yarn and there knits such proportion of a complete course as the number of dial needles 10 bears to the complete circle of cylinder needles 2. This action is repeated at each feed so that, assuming there are thirty-two feeds, thirty-two complete courses are knitted at each revolution of the needle cylinder, the said dial needles participating as described with the cylinder needles 2, so that a yarn is taken by each dial needle 10 of the segment 10 of dial needles at each yarn feed, thus knitting the rib stripe upon all the dial needles 10 in cooperation with the corresponding cylinder needles.

Obviously the character of the knitting may be varied in the plain-knit portion of the fabric as well as in the rib-knit portion or portions thereof, as fully described in my said Patent No. 2,414,424.

In lieu of the cam disk 22 having the continuous cam track arranged to provide four places at each of which the dial needles 10 are projected and retracted, I may provide any other suitable shape of rotating, dial-needle projecting-and-retracting cam member for the purpose. The shape of the cam track of the cam disk should be such that the dial needles are properly projected and retracted in synchronism with the movements of the cylinder needles at the same feed to cause all the said segment 10 of dial needles to knit with the corresponding cylinder needles that participate in the knitting of the stripe of ribbed work.

As hereinbefore set forth, the term "dial" is employed by me generically both in the specification and in the claims to indicate either a complete circular disk or a sufficiently large segment of a circular disk to accommodate the dial needles that are employed to knit a longitudinally extending stripe of rib knitting of the desired width.

Having thus described an illustrative embodiment of the invention, it is to be understood that although specific terms are employed, they are used in a generic and descriptive sense, and not for purposes of limitation, the scope of the invention being set forth in the following claims.

What I claim is:

1. A circular, independent needle, knitting machine for knitting a unitary, tubular, plain-knit fabric of indefinite length having at least one relatively narrow, walewise extending area of rib knitting, which relatively narrow area or areas may be thereafter cut lengthwise on a median line thereof to provide at least one plain-knit, flat fabric having rib-bent, walewise extending, relatively narrow, side edge portions rendered non-

curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles at a plurality of spaced stations about said needle cylinder, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles, said cam means being carried by the dial and rotating therewith to project and retract the segment of dial needles, and synchronizing means cooperating with and co-related to said cam means for the dial needles and with the several yarn feed stations, thereby to project and to retract the said relatively narrow segment of dial needles at such times that said dial needles take yarn in each course at each of said spaced yarn feed stations, always in and only in knitting the same wales and in accurately timed relation with the projection and retraction of the cylinder needles and thus create accurate marginal vertical lines of rib knitting at the marginal wales of such relatively narrow rib-knitted area or areas.

2. A tubular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of yarn feeds, at each of which the cylinder needles are projected to take yarn by the cams of the cam ring, and at each of which feeds the segment of dial needles is projected to take yarn, said cam means consisting of a member rotatable upon its own axis and having a dial needle projecting and retracting cam formation, and means to rotate said cam means upon its own axis in synchronism with the projection and retraction of the cylinder needles.

3. A tubular, independent needle, knitting machine for knitting a unitary, tubular, plain-knit fabric of indefinite length having at least one

relatively narrow, walewise-extending area of rib knitting, which relatively narrow area or areas may be thereafter cut lengthwise on a median line thereof to provide at least one plain-knit flat fabric having rib-knit, walewise extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of yarn feeds, at each of which the cylinder needles are projected to take yarn by the cams of the cam ring, and at each of which feeds the segment of dial needles is projected to take yarn, the cam means including a disk rotatable upon its own axis and having a continuous dial needle projecting and retracting cam track, and means to rotate said disk upon its own axis in synchronism with the projection and retraction of the cylinder needles.

4. A tubular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of yarn feeds, at each of which the cylinder needles are projected to take yarn by the cams of the cam ring, and at each of which feeds the segment of dial needles is projected to take yarn, the cam means including a disk rotatable upon its own axis and having a continuous dial needle projecting and retracting cam track, and means to rotate said disk upon its own axis in synchronism with the projection and retraction of the cylinder needles, the said continuous dial

needle projecting and retracting cam track consisting of a number of needle projecting and retracting cam lobes.

5. A circular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit flat fabric having rib-knit, walewise extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, the needle cylinder and the dial being rotatable and the cam ring being stationary, means to feed yarns into the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of stationary yarn feeds, the cam means including a disk rotatable upon its own axis and means to rotate said disk upon its own axis in synchronism with the projection of the cylinder needles, and also to cause said cam means to travel with the needle cylinder about the axial center of the needle cylinder, so that at each yarn feed said cam means for the segment of dial needles projects the said segment of dial needles to take yarn with the cylinder needles projected at the corresponding yarn feed.

6. A circular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit flat fabric having rib-knit, walewise extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, the needle cylinder and the dial being rotatable and the cam ring being stationary, means to feed yarns into the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of stationary yarn feeds, means to project and retract

the dial needles at each feed comprising a support for said cam means consisting of a narrow member extending radially at the upper face of the dial, a dial needle projecting and retracting cam disk pivotally mounted upon its own axis upon said narrow member near the outer end of said member, a gear mounted at the longitudinal axis of the needle cylinder, and gearing between said gear and said cam disk to rotate said cam disk upon its own axis as it travels on said narrow member about the needle cylinder, thereby to cause said dial needles to knit in synchronism with the cylinder needles at each feed.

7. A circular, independent needle, knitting machine for knitting a unitary, tubular, plain-knit fabric of indefinite length having at least one relatively narrow, walewise-extending area of rib-knitting, which relatively narrow area or areas may be thereafter cut lengthwise on a median line thereof to provide at least one plain-knit flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, the needle cylinder and the dial being rotatable and the cam ring being stationary, means to feed yarns into the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a multiplicity of stationary yarn feeds, the cam means to project and retract the dial needles consisting of a circular cam disk rotatable upon its own axis and having on its under face a continuous cam track having four cam lobes, and means to rotate said cam disk in synchronism with the projection of the cylinder needles, and also to cause said cam disk to travel bodily with the needle cylinder about the axial center of the needle cylinder, so that at each of the yarn feeds the segment of dial needles is projected to take yarn with the cylinder needles projected at the corresponding yarn feed.

8. A circular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit, flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means to feed yarns to the cylinder needles, a dial having radial grooves therein, independent dial needles supported only in such dial grooves as to be sufficient in number to knit only said relatively narrow area or areas of rib knitting, and thereby

providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, a sinker ring in cooperating relation with the needle cylinder, the needle cylinder and the dial being rotatable and the cam ring being stationary, a plurality of stationary yarn feeds, the cam means to project and retract the dial needles consisting of a cam disk rotatable upon its own axis, and means to rotate the said cam disk upon its own axis in synchronism with the projection of the cylinder needles, and also to cause the said cam means to travel with the needle cylinder about the axial center of the needle cylinder, so that at each yarn feed the said cam means for the segment of dial needle projects the said segment of dial needles to take yarn with the cylinder needles projected at the corresponding yarn feed.

9. A circular, independent needle, knitting machine for knitting a unitary, tubular, plain-knit fabric of indefinite length having at least one relatively narrow, walewise-extending area of rib knitting, which relatively narrow area or areas may be thereafter cut lengthwise on a median line thereof to provide at least one plain-knit flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, the cam means for operating the dial needles being carried at the upper face of the dial and rotating therewith to project and retract the segment of dial needles.

10. A circular, independent needle, knitting machine for knitting a unitary, tubular, plain-knit fabric of indefinite length having at least one relatively narrow walewise-extending area of rib knitting, which relatively narrow area or areas may be thereafter cut lengthwise on a median line thereof to provide at least one plain-knit flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said rel-

atively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, the cam means to project and retract the dial needles being rotatable upon its own axis and being also relatively revolved with the dial and the needle cylinder, so as to cause the segment of dial needles to knit at each feed with the corresponding cylinder needles.

11. A circular, independent needle, knitting machine for knitting a unitary, tubular, plain-knit fabric of indefinite length having at least one relatively narrow, walewise extending area of rib knitting, which relatively narrow area or areas may be thereafter cut lengthwise on a median line thereof to provide at least one plain-knit, flat fabric having rib-knit, walewise extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of yarn feeds, the cam means for projecting and retracting the dial needles being carried by the upper face of the dial, and being rotatable upon its own axis and also relatively revolvable with the dial and dial needles, the said dial needles being projected and retracted at each yarn feed so as to knit at each yarn feed.

12. A circular, independent needle, knitting machine for knitting a unitary, tubular, plain-knit fabric of indefinite length having at least one relatively narrow, walewise extending area of rib knitting, which relatively narrow area or areas may be thereafter cut lengthwise on a median line thereof to provide at least one plain-knit, flat fabric having rib-knit, walewise-extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, the needle cylinder and the dial being rotatable and the cam ring being stationary, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively

narrow segment of dial needles in such timed relation with the projection and retraction of the cylinder needles as to cause the dial needles to take the knitting yarns and to knit rib fabric only at said relatively narrow area or areas, said means to feed yarn comprising thirty-two stationary yarn feeds, the cam means to project and retract the dial needles consisting of a circular cam disk rotatable upon its own axis and having on its under face a continuous cam track having four cam lobes, and means to rotate said cam disk in synchronism with the projection of the cylinder needles, and also to cause said cam disk to travel bodily with the needle cylinder about the axial center of the needle cylinder, so that at each of the thirty-two yarn feeds the segment of dial needles is projected to take yarn with the cylinder needles projected at the corresponding yarn feed.

13. A circular, independent needle, knitting machine for knitting a unitary, tubular, plain-knit fabric of indefinite length having at least one relatively narrow, walewise extending area of rib knitting, which relatively narrow area or areas may be thereafter cut lengthwise on a median line thereof to provide at least one plain-knit, flat fabric having rib-knit, walewise extending, relatively narrow, side edge portions rendered non-curling after such cutting by reason of said rib-knit areas which are each largely exceeded in width by the width of the plain-knit portion of said tubular fabric, said knitting machine comprising a needle cylinder having a circle of independent needles, a surrounding cam ring, means relatively to rotate said needle cylinder and cam ring, means to feed yarns to the cylinder needles, a dial having radial grooves therein, independent dial needles supported only in such dial grooves as to be sufficient in number to knit only said relatively narrow area or areas of rib knitting, and thereby providing a relatively narrow segment of dial needles, cam means to project and retract said relatively narrow segment of dial needles in such timed relation with the projection and retraction of the cylinder needles as to cause the dial needles to take the knitting yarns and to knit rib fabric only at said relatively narrow area or areas, said means to feed yarn comprising a plurality of yarn feeds, at each of which the cylinder needles are projected to take yarn by the cams of the cam ring, and at each of which feeds the segment of dial needles is projected to take yarn, the cam means including a member movable upon its own axis and having a dial needle projecting and retracting cam track, and means to rotate said movable member upon its own axis to synchronism with the projection and retraction of the cylinder needles.

BROOKS STEVENS, JR.
